UNITED STATES PATENT OFFICE

PAUL NAWIASKY AND LUDWIG EIFFLAENDER, OF LUDWIGSHAFEN-ON-THE-RHINE, GERMANY, ASSIGNEES TO GENERAL ANILINE WORKS, INC., OF NEW YORK, N. Y., A CORPORATION OF DELAWARE

PRODUCTION OF ANTHRAQUINONE-AZINES

No Drawing. Application filed October 27, 1927, Serial No. 229,258, and in Germany October 3, 1926.

The present invention relates to improvements in the production of N-dihydro-1,2,1',2'-anthraquinone-azines.

It is known that the valuable blue dyestuff 5 N-dihydro-1,2,1',2'-anthraquinone-azine can be obtained by the action of fused caustic alkali on 2-aminoanthraquinone, with or without the addition of oxidizing agents, the melt being poured into water and oxidized with 10 air. In order to improve the yield, it has also been proposed to add to the melt salts of low fatty acids, such for example as potassium formate, potassium acetate, and the like, in the presence, if required, of an inert diluent, or to add alcoholates or phenolates, such 15 as sodium butylate, sodium phenolate, and the like.

We have now found that still better yields 20 of the said dyestuff or of its derivatives when starting from substituted 2-amino-anthraquinone, may be obtained if salts of low fatty acids, namely of formic, acetic or propionic acid are added to the caustic alkali melt in conjunction with organic compounds containing 25 at least 3 carbon atoms in their molecule and also containing a metal attached to an oxygen atom. As examples of such organic compounds may be mentioned salts of fatty acids with at least 4 carbon atoms, 30 in particular soaps, further metal alcoholates or phenolates. For example, sodium acetate may be added in conjunction with potassium phenolate, or with sodium glycerate, sodium amylyate, potassium butyrate 35 (normal or iso-), potassium valerate, soap and the like. Other specific examples of suitable additions will be specified hereinafter. According to the present invention the caustic alkali melt may be carried out with an addition of oxidizing agents or also in the absence of such agents, and preferably with fused caustic potash-soda.

The following examples will further illustrate the nature of the said invention, but the 45 invention is not limited thereto. The parts are by weight.

Example 1

75 parts of dehydrated sodium acetate are 50 introduced into a melt of 2000 parts of caustic

potash-soda at a temperature of 250° C., 45 parts of sodium glycerate being then added, and the mixture stirred until uniform distribution has taken place. The mixture is next cooled down to a temperature of 210° 55 C. and 500 parts of β -aminoanthraquinone are introduced in such a way that the temperature does not rise above 230° C. The whole mixture is maintained at a temperature of 225° C. until no further increase in the production of dyestuff occurs, and β -aminoanthraquinone can no longer be detected. The melt is then treated in the usual manner.

Example 2

15 parts of dehydrated sodium acetate are 60 stirred into 200 parts of a mixture, in molecular proportions, of caustic potash and soda at a temperature of about 200° C., 20 parts of soap being then added. Thereupon 75 parts 65 of β -aminoanthraquinone are introduced, and the mixture is stirred at a temperature of from 200 to 210° C. until the production of the dyestuff ceases to increase. The separation of the dyestuff is effected in the usual 70 manner.

The soap may be replaced, with equal effect, by cellulose pitch, i. e. the pitchy residue obtained by evaporating sulfite cellulose waste liquor, salts of diisopropynaphthalene sulfonic acid or bile acid, Turkey-red oil, acids obtained by the sulfonation of brown-coal tar, and the like.

Example 3

75 parts of dehydrated sodium acetate are 80 introduced into a melt of 2000 parts of caustic potash-soda at a temperature of 250° C., 45 parts of potassium isobutyrate being then added and the mixture stirred until uniform 85 distribution has taken place. The mixture is then cooled down to a temperature of 210° C. and 500 parts of β -aminoanthraquinone are introduced in such a way that the temperature does not rise above 230° C. The 90 whole mixture is maintained at a temperature of 225° C. until the production of dyestuff ceases to increase and β -aminoanthraquinone can no longer be detected. The melt is then 95 treated in the usual way.

What we claim is:

1. The process of producing N-dihydro-1,2,1',2'-anthraquinone-azine which comprises subjecting 2-amino-anthraquinone to the action of a caustic potash-soda melt in the presence of sodium acetate in conjunction with an alkali metal butyrate.
2. The process of producing N-dihydro-1,2,1',2'-anthraquinone-azines which comprises subjecting a 2-amino-anthraquinone to the action of a caustic alkali melt in the presence of a salt of a low fatty acid in conjunction with an alkali metal compound of an alcohol containing at least three carbon atoms.
3. The process of producing N-dihydro-1,2,1',2'-anthraquinone-azines which comprises subjecting a 2-amino-anthraquinone to the action of a caustic potash-soda melt in the presence of a salt of a low fatty acid in conjunction with an alkali metal compound of an alcohol containing at least three carbon atoms.

In testimony whereof we have hereunto set our hands:

PAUL NAWIASKY.
LUDWIG EIFFLAENDER.
